UNITED STATES PATENT OFFICE.

EDWIN DEWHURST MCLEAN, OF MARISSA, ILLINOIS.

STOVE OR FURNACE.

SPECIFICATION forming part of Letters Patent No. 600,795, dated March 15, 1898.

Application filed February 25, 1897. Serial No. 625,007. (No model.)

To all whom it may concern:

Be it known that I, EDWIN DEWHURST MCLEAN, a citizen of the United States, residing at Marissa, St. Clair county, State of Illinois, have invented a certain new and useful Improvement in Stoves or Furnaces, of which the following is a full, clear, and exact description, reference being had to the accompanying drawings, forming a part of this specification.

My invention relates to that class of stoves or furnaces capable of employment as either downdraft or updraft, and is an improvement on the device set forth in my Patent No. 574,210, dated December 29, 1896.

My invention consists in features of novelty hereinafter fully described, and pointed out in the claims.

Referring to the drawings, Figure I illustrates a vertical section through the central portion of the stove or furnace, the section being taken on the line indicated by II, Fig. II. Fig. II is a top view of the stove-base from which the remainder of the stove or furnace has been removed. Fig. III illustrates a horizontal section taken on line III III, Fig. I.

In the drawings, 1 designates the base, on which is seated a pot 2, that is surmounted by 30 the casing 3.

The stove or furnace may be fed through a side door 4, or may be self-fed by employing a magazine 5, surmounted by a cover 6, located on top of the casing.

35 7 designates a shaking-grate mounted on brackets 8, secured to the casing by rivets or other suitable means. The shaking-grate is provided with an arm 9, designed to be engaged by a suitable implement inserted 40 through an opening 10, protected by a door 11. The opening 10 may also be employed to admit air to the interior of the stove or furnace both above and beneath the grate.

45 12 designates a basket-grate composed of sections 12^a, each section having an upper solid portion 12^b, said portions constituting the fire-pot lining.

50 13 designates an outlet in the rear of the casing, through which the products of combustion pass either horizontally or downward, as indicated by the arrows.

14 designates the fire-chamber, and 15 the combustion-chamber beneath the grates.

16 designates a main flue extending from the base, and 17 an auxiliary flue located between the fire-chamber and the main flue, the two flues being separated by a division-wall 18, said wall extending down into the combustion-chamber to a considerable distance beneath the grates in the same manner and 55 for the same purpose as set forth in my patent hereinbefore mentioned. The division-wall 18 is formed with an offset portion 18^a at its upper end and an opening 19, that permits communication between the flues or from the 60 fire-chamber 14 to the main flue.

20 designates a single double-winged damper pivotally hung intermediate of its edges at the upper end of the division-wall 18. This damper is arranged to be swung into 70 the position shown by full lines in the drawings, where it closes the opening 19, or swung into the position indicated in dotted lines, Fig. I, where it prevents upward passage through the main flue from the combustion- 75 chamber, closes the upper end of the auxiliary flue, and causes the products of combustion to pass directly from the fire-chamber 14 to the upper end of the main flue and out to the chimney.

80 One end of the shaft of the damper extends to the exterior of the stove or furnace and has attached to it an operating-crank 21, by means of which the damper may be operated, the crank being provided with a knob 22. 85 On the crank is a boss 23, to which is connected a rod 24, that passes through the stove or furnace casing and a tube 25 therein to the front of the stove or furnace. The forward end of the rod 24 is provided with a 90 knob 26, that may be grasped to operate the damper from in front of the stove or furnace.

27 designates the ash-pit door, which carries on its inner side a tapered lug 28.

29 designates a rocking rod pivotally mounted in hangers 30, attached to the base 1. The forward end of this rocking rod has an offset arm 31, and the rear end is formed into a crank-arm 32, provided with an eye 33.

34 designates a rod passing through the 100 main flue, having at its lower end an eye 35, that interlocks with the eye 33 of the crank-

arm 32. The upper end of the rod 34 is formed into a loop 36, that receives a link 37.

38 is an eye attached to the damper 20, in which eye the link 37 is seated.

5 The purpose of the damper connection leading to the ash-pit door is to provide for the automatic opening of the damper on the opening of the ash-pit door, a result accomplished by virtue of the weight of the parts, the object of causing the damper to automatically operate on the opening of the ash-pit door being to cause the products of combustion to pass directly from the fire-chamber to the main flue on the opening of the ash-pit door.

10 15 Otherwise such products of combustion would descend on the opening of the ash-pit door and escape into the room containing the stove or furnace. When the ash-pit door is again closed, the rocking rod 29 is turned by the 20 tapered lug 28 striking the arm 31, and the crank-arm 32 is elevated, thereby raising the rod 34, after which the damper 20 may be operated by grasping the knob 22 or the knob 26.

25 I claim as my invention—

1. In a stove or furnace, the combination of a casing, an outlet from said casing, a main flue, an auxiliary flue, said outlet being arranged to communicate with both of said flues, a single double-winged damper common to both flues and arranged to control both of said flues, an ash-pit door, and means whereby said damper is operated on the opening of said ash-pit door, substantially as set forth. 30

2. In a stove or furnace, the combination of a casing, a main flue, an auxiliary flue, a single double-winged damper common to both flues and arranged to control both of said flues, a rod loosely connected to said damper, a rocking rod pivotally mounted at the base of the stove or furnace and connected to said rod, an ash-pit door, and a tapered lug carried by said door, arranged to operate said rocking rod, substantially as set forth. 40

EDWIN DEWHURST McLEAN.

In presence of—
E. S. KNIGHT,
N. FINLEY.
